COMBINED BRACKET AND DISPOSABLE FILTER FOR HOME AQUARIUMS

David D. Lovitz, Short Hills, N.J., assignor to Sternco
Industries, Inc., Harrison, N.J., a corporation of New
Jersey

Filed Apr. 25, 1969, Ser. No. 16,900

Term of patent 14 years

Int. Cl. D23—01

U.S. Cl. D23—4

FIG. 1

FIG. 2

FIG. 4

FIG. 1 is a perspective view of a combined bracket and disposable filter for home aquariums showing my new design.

FIG. 2 is an exploded perspective view of the combined bracket and filter of FIG. 1.

FIG. 3 is a rear view of the filter component of FIGS. 1 and 2, the bracket being omitted for purposes of disclosure.

FIG. 4 is a bottom plan view of FIG. 1, it being understood that the apertures are continuous across the bottom surface.

FIG. 5 is a front view of FIG. 1.

FIG. 6 is a side view of FIG. 1.

FIG. 7 is a rear view of FIG. 1.

The aquarium is fragmentarily shown in broken lines in FIG. 1 for illustrative purposes only.

The fragmentary aquarium and filter attachments are shown in broken lines in FIG. 1 for illustrative purposes only.

I claim:

The ornamental design for a combined bracket and disposable filter for home aquariums, as shown and described.
